UNITED STATES PATENT OFFICE.

LEVI S. GARDNER, OF CEDAR GROVE, LOUISIANA.

CARBURETER.

1,221,164.

Specification of Letters Patent.

Patented Apr. 3, 1917.

Application filed September 4, 1914. Serial No. 860,136.

To all whom it may concern:

Be it known that I, LEVI S. GARDNER, a citizen of the United States, residing at Cedar Grove, parish of Caddo, State of Louisiana, have invented a certain new and useful Improvement in Carbureters, and declare the following to be a full, clear, and exact description of the same, such as will enable others skilled in the art to which it pertains to make and use the same, reference being had to the accompanying drawings, which form a part of this specification.

My invention has for its object to produce an efficient and reliable carbureter consisting of but a few simple parts.

Viewed in one of its aspects, my invention may be regarded as having for its object the production of a carbureter adapted, without the use of moving parts, to maintain the most advantageous proportions between air and fuel at all speeds of the engine to which the carbureter is connected.

The various features of novelty whereby my invention is characterized will herein-after be pointed out with particularity in the claims; but for a full understanding of my invention and of its objects and advantages, reference may be had to the following detailed description taken in connection with the accompanying drawing, wherein:

Figure 1 is a central vertical section through a carbureter arranged in accordance with one form of my invention;

Fig. 2 is a section corresponding to Fig. 1, illustrating only a portion of the carbureter, slightly modified; and

Fig. 3 is a central vertical section through a carbureter arranged in accordance with a still further form of my invention.

The principal problem to be solved by carbureters is the maintenance of the proper proportions between the fuel and the air at all speeds of the engine. At low speeds a richer mixture is required than at higher speeds. In the most common type of carbureter the dilution of the mixture at the higher speeds is obtained by opening an auxiliary air passage which permits air to enter the mixture at a point between the fuel nozzle and the engine. This construction involves the use of movable valves and springs and, because extremely accurate and delicate adjustments are essential, it is almost impossible to obtain uniform results. In accordance with my invention I secure the

necessary dilution of the mixture automatically as the speed increases and without using any moving or movable parts subject to wear or to inaccurate adjustments.

Referring first to Fig. 1 of the drawing, 1 represents a tubular member constituting the body of the carbureter, the member 1 being open at both ends. Surrounding the member 1 is a suitable fuel reservoir consisting of a flange, 2, formed integral with the member 1 and constituting the top of the reservoir, together with a cup-shaped member, 3, arranged beneath the flange 2 and suitably secured in place upon the member 1 with its mouth closed by the flange. The cup 3 may conveniently be held in place by means of a nut, 4, screwed upon the lower or inlet end of the member 1. In the reservoir is a suitable float, 5, controlling a fuel inlet valve, 6, by means of which a constant level of fuel is maintained in the reservoir. The member 1 is preferably, though not necessarily, made in the shape of an ordinary Venturi tube.

On one side of the member 1 at a point just above the bottom of the reservoir is an outwardly-projecting boss, 7, through which is bored a hole, 8, large enough to receive the end of an L-shaped pipe, 9. The lower end of the pipe 9 fits into the hole 8 while the upper portion lies within the member 1 and has its outlet end terminating in the vicinity of the narrowest portion of the passage through the body member. A small hole, 10, is bored through the boss 7 in a position to place the lower end of the tube 9 in communication with the interior of the fuel reservoir. The end of the hole 8 within the fuel reservoir is closed by a plug 11. Up to this point the construction described is simply typical of carbureters in general except that the tubular member 9 is larger in diameter, particularly at the outlet end, than the usual nipple or nozzle.

In order to provide for the automatic dilution of the charge I employ an air tube, 12, slightly smaller in external diameter than the interior diameter of the tube 9 so that when the tube 12 is inserted into the outlet end of the tube 9 there remains a narrow annular passage between the walls of the two tubes, this passage being the effective discharge passage for the fuel. In the arrangement shown, the tube 12 projects upwardly above the tube 9 and is bent laterally and

secured in an opening passing through the wall of the body member 1 of the carbureter; the outer end of the tube being open so as to place the interior thereof in direct communication with the atmosphere. The lower end of the tube 12 is perforated at points within the tube 9 and below the normal liquid level, 15, in the tube 9. In the arrangement shown, the perforating is accomplished by forming in the lower end of the tube 12 a series of small holes, 14, distributed one above the other.

The operation is as follows: The fuel reservoir and the tube 9 being filled with liquid fuel to the level indicated by the dotted line 15 which is just below the top of the tube 9; then when the engine starts, the inrushing air through the main air passage in the carbureter draws the liquid fuel out through 20 the annular discharge passage between the upper end of the tube 9 and the tube 12, just as is done in the ordinary carbureter. The area of the supply port 10 is sufficient to permit the fuel to flow from the reservoir to the 25 tube 9 at the proper rate to maintain approximately the normal liquid level in the tube 9 at low speeds. The effective discharge outlet from the tube 9 is greater in area than the supply port 10 so that as the speed of 30 the engine and the suction in the carbureter increase, the liquid will be drawn out of the tube 9 faster than it is supplied thereto until either the liquid level in the tube drops to the highest point of perforation in the tube 35 12 or a breaking up of the stream of liquid flowing through the annular passage takes place and serves to uncover the highest point of perforation in the tube 12. As soon as this occurs, air begins to flow down through 40 the tube 12 and is discharged into the tube 9 where it mixes with the liquid which is being drawn from the latter tube and serves to dilute the same so that, instead of having simply a stream of liquid fuel drawn out of 45 the upper end of the tube 9 by the suction of the engine, there is obtained a mixture of air and fuel. In other words, the air for diluting the charge is introduced into the fuel before the latter is drawn out of what corresponds to the nozzle or nipple in the ordinary carbureter instead of being introduced into the main charge at a point between the nozzle or nipple and the engine as in the old form of carbureters. In other words, the 50 auxiliary air is introduced into what may be termed a column or stream of fuel flowing from the reservoir into the main air passage in the carbureter. As the suction of the engine increases still further additional air 55 ports in the tube 12 are uncovered so that the amount of air mixed with the fuel in the tube 9 is increased. It will therefore be seen that the liquid fuel in the tube 9 serves as a valve to control the admission of auxiliary air, stopping the flow of auxiliary air at

low speeds and permitting gradually increased amounts of air to be drawn in as the speed of the engine increases.

Fig. 2 illustrates the same carbureter as Fig. 1 with the addition of a needle valve, 70 16, for varying the size of the port 10.

In Fig. 3 I have illustrated an arrangement in which the tube 17, corresponding to the tube 12 lies wholly within the main air passage in the carbureter and opens at 75 its upper end into this passage, while the lower end, within the tube 9, has a restricted port, 18, therein. In this arrangement air or a combustible mixture may flow into the tube 9 through the tube 17. This arrangement permits a modified action to be obtained. Thus the tube 17 may be made long enough to extend into proximity to the usual butterfly throttle valve 19, the upper end being preferably bent laterally so as to bring the 80 open end of the tube just below the extreme edge of the throttle valve at one end of a radius extending at right angles to the axis of rotation of the valve. This arrangement permits the throttle valve to control the upper end of the tube 17; but the principal result obtained is that as the throttle valve is opened slightly the air or mixture of air and fuel passes the upper end of the tube 17 at a high velocity and therefore fuel will 85 be drawn out of the upper end of the tube 9 and also out of the upper end of the tube 17. As the speed of the engine is increased or, in other words, as the throttle valve is opened more widely, the effect of the air or charge traveling past the upper end of the tube 17 is rapidly diminished, while the effect at the discharge end of the tube 9 is increased. The result is that the tube 17 no longer acts as a conduit for combustible but, 90 I believe, actually allows air to flow downwardly through the same and thus dilute the fuel which is being drawn out of the tube 9 just as in the other form air is supplied through the tube 12; the air flowing down 95 through the tube 17 being, however, carbureted air instead of plain atmospheric air.

While I have illustrated and described with particularity only a few forms of my invention, it will of course be understood that the principle of my invention may be embodied in a great many different mechanical constructions and I therefore do not desire to be limited to the structural details illustrated and described; but intend to 100 cover all forms and arrangements which come within the terms employed in the definitions of my invention constituting the appended claims.

I claim:

1. In a carbureter, a body member in the form of a Venturi tube, a constant level reservoir surrounding the lower end of said body member, an L-shaped delivery tube having one arm lying at the axis of the body 105

member and terminating in the vicinity of the contracted neck thereof and having its other arm extending laterally to the side of the body member and communicating with said reservoir, and an air tube, smaller in diameter than the interior diameter of said delivery tube, extending at its lower end into the latter tube and having its upper end open.

10 2. In a carbureter, a body member in the form of a Venturi tube, a constant level reservoir surrounding the lower end of said body member, an L-shaped delivery tube having one arm lying at the axis of the body member and terminating in the vicinity of the contracted neck thereof and having its

other arm extending laterally to the side of the body member and communicating with said reservoir, and an L-shaped air tube, 20 smaller in diameter than the delivery tube, having one arm projecting into the upper end of said delivery tube and having its other arm extending laterally to the side of the body member and communicating with the outside atmosphere.

25

In testimony whereof, I sign this specification in the presence of two witnesses.

LEVI S. GARDNER.
